UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP.

DETACHABLE FILLER FOR MEMORANDUM BOOKS.

Application filed October 16, 1922. Serial No. 594,676.

To all whom it may concern:

Be it known that I, JOHN SCHADE, a citizen of the United States, residing at the city of Holyoke, in the county of Hampden 5 and State of Massachusetts, have invented certain new and useful Improvements in Detachable Fillers for Memorandum Books; and I do declare the following to be a full, clear, and exact description of the invention, 10 such as will enable others skilled in the art to which it appertains to make and use the same.

This invention relates to certain new and useful improvements in detachable fillers for 15 memorandum books, and the primary object of the invention is to provide a book of this character which enables the filler to be easily and quickly applied to, and removed from the book and a new filler to be substituted as 20 desired or found necessary.

A further object of the invention is to provide means for removably securing the 25 filler in position which is devoid of any moving or other parts that require manipulation in either the attachment or detachment of the filler.

Still further the invention aims to provide 30 filler securing means which can be easily and quickly secured in operative relation to the book, and which also enables economical production of the book.

The invention has still further and other 35 objects which will be later set forth and manifested in the course of the following description.

In the drawings:

Figure 1, is a side edge elevation of the 40 invention;

Figure 2, is a top plan view of the cover 45 in full or flat open position and with the filler removed, and

Figure 3, is a plan view of the blank from 50 which the attaching clips are formed.

In proceeding in accordance with the 55 present invention, a substantially C-shaped member is employed having a straight long leg or body, and inturned ends or arms 2, 2 each of which lies approximately parallel to the body 1. The ends or arms 2, 2 form attaching means for the body and are secured to the cover 3 of the book at the line of fold of the latter by means of clips 4 each of which latter is curved or channeled or of

approximately U-cross section. The clips 4 engage the line of fold of the cover and 55 overlie same and are formed on each side with a pair of spurs 5, the latter penetrating the cover and being bent or clinched over and onto the arms 2, 2 from opposite sides of the arms, so as to hold the arms firmly to the cover. The body 1 is thus held spaced from the cover so as to receive the filler F in such space. The filler F is composed of a series of leaves transversely sewed or otherwise connected together centrally of the 60 length thereof and is formed of such thickness so as to permit same to be threaded through the space between body 1 and arms 2 and with the line of connection in register with the body and arms thereof. The clips 65 also afford reinforcements for the back edge or line of fold of the cover and can be economically produced by stamping, as shown in Figure 3.

From the above it will be apparent that 70 the entire structure involves but three parts namely the filler-holding member and its two securing clips thus affording a simple structure which can be economically produced and assembled. The holding member may be formed of wire, the structure being devoid of all moving parts. The attaching member holds the filler in place by frictional contact therewith and by virtue of the inherent tendency of the leaves to curve outwardly.

What is claimed is:

1. In a memorandum book, a foldable 90 cover, an attaching member having a body and ends offset therefrom, clips engaged over the back of the cover and having spurs clinched over the body ends to hold the body spaced from the cover, and a filler threaded through said space.

2. In a memorandum book, a foldable 95 cover, a filler, a filler-holding member having portions spaced from the cover and having parts engaging the cover, and means engaged with the back of the cover and having parts extending through the cover and engaged with said parts of the filler holding member to secure the latter in position.

In testimony whereof I affix my signature 105 hereto.

JOHN SCHADE.
